UNITED STATES PATENT OFFICE

MARTIN ETCHART, HIJO, OF BUENOS AIRES, ARGENTINA

MACHINE FOR SHARPENING WOODEN TOOTHPICKS AND OTHER SIMILAR ARTICLES

Application filed July 10, 1930. Serial No. 466,979.

The present invention refers to improvements in machines for sharpening wooden toothpicks and other similar articles, by the use of which it is possible to obtain a greater 5 perfection and finish and principally a maximum and notable production, thereby reducing labour and cost.

The invention is carried out as herein-after described, reference being had to the 10 accompanying drawings, wherein:

Fig. 1 is a front view of the machine;

Fig. 2 is a view of certain details of the left side of the machine;

Fig. 3 is a view of certain details of the 15 right side of the machine.

Construction

The construction comprises an essential element which is the central wheel, where 20 the sharpening of the toothpicks or similar articles takes place, these being received already cut and rounded by other machines, the machine of my invention effecting the sharpening at both ends of the toothpick or 25 the like, although this operation can be carried out at one end only if desired.

The central part is composed of a central wheel *a* moved by an interior shaft. Around the central wheel *a* are found the rings *c* 30 forming at first sight one sole part, but said rings *c* move independently of the wheel *a*. These rings *c* carry teeth *c*¹, and the latter in turn carry the toothpicks or the like. In Fig. 1 a portion only of the toothpick carriers *c*¹ are shown in the lower part, for 35 the purpose of better illustration. The teeth *c*¹ form a solid body with the two rings *c*, but not with the central wheel *a*, which they allow to turn freely.

On each side of the wheel formed by the central *a* and rings *c*, are placed two sharpening wheels *d*, driven by shafts *e*, which are almost entirely interior, (Fig. 1). These shafts are supported by two circular parts *f*, 45 in the interior of which are placed the ball bearings or of any other type *g* which may be found convenient; the circular parts *f* may be regulated towards either side on account of being sustained by the supports 50 *h*² which have a handle *i* turning an eccen-

tric *j* which forms solid body with the circular parts *f*. This movement is what allows the regulation of the sharpening wheels, and what constitutes one of the principal characteristics of the present improvements.

The sharpening wheels *d* are moved by the shaft *e* by means of pulleys *e*¹.

In quarter circle, in the back part, is found the pad *s* (Figs. 1 and 3) regulated also by the lever *i*² which puts in action the eccentric *j*¹.

A pinion *k* placed on the shaft *m* (Fig. 2) governs a gear wheel *n* and the latter governs another wheel *n*¹ carrying a shaft on which is placed a pinion *o* which meshes 65 with the carriers *c*¹ (Figs. 1 and 2).

The shaft *m* is put in movement by the pulley *p* by means of ordinary belting, the same as pulleys *e*¹.

All shafts are supported by means of 70 bases or columns *q* and *q*¹, or by any other adequate means.

Working

This is quite simple. The machine is 75 started by usual means, that is, by the pulleys *e*¹ with their respective belting and the pulley *p* with its other belting.

The pulley carrying the pinion *k* governs the gear wheel *n*, and this in turn the one 80 indicated by *n*¹, which, as has already been stated, carries a shaft in the centre of which is placed a pinion *o* (Fig. 1), which moves the stick carriers *c*¹ which mesh perfectly with said pinions *o*.

The central wheel *a* is moved in turn by the shaft *e*, and obliges, by its rapid movement, the toothpicks or the like to revolve or turn vertiginously, each one of which becomes automatically placed, by reason of its own weight, in each of the spaces that exist between each tooth *c*¹ of the rings *c*, for which purpose there is previously placed a changeable deposit *r* (Fig. 3). On reaching the upper part, and whilst descending a fourth 90 part of the circumference, the toothpicks or the like are compressed by the pad *s* (Fig. 3). On being compressed, the emery surface, or surface of any other type which may be 95 found convenient for the purpose, rubs and 100

reduces the ends of the toothpicks or the like, sharpening them in an entirely satisfactory manner. When greater or less sharpening is desired, or if it is required to suppress same altogether at one end of the toothpick or the like, this is obtained by moving the lever *i*, which puts in movement the eccentric *j* and changes the position of the entire central part *f*, the construction of this central part *f* and the reducing wheels *d* which revolve in same, being one of the principal characteristics of the present invention owing to their regularity.

Once the toothpicks or the like have passed a fourth of a circle behind (Fig. 3), they fall by reason of their own weight in a box or other receiver.

As has been previously stated, the pressure of the toothpicks or the like against the sharpening wheels is effected by the pad *s*, which will have been regulated by an eccentric *j*, as is seen in Fig. 3.

It will be evident that the machine is placed on a bench in order that it will be at the desired height for the workman that is in charge of same.

The material employed in the construction of the different parts of the machine according to my invention, as also the size of same, will be those found most convenient in practice, bearing in mind the distinct functions to be performed.

Having thus described my invention, what I claim as new and desire to secure by Letters Patent, is:

1. Improvements in machines for sharpening wooden toothpicks and like articles, characterized by two wheels *d* of emery or the like, with inclined faces, which are on either side of a central wheel *a*, surrounded by the rings *c* carrying the teeth *c'* conveniently spaced apart, these two sharpening wheels being governed by the shafts *e* and these latter by the corresponding pulleys *e'*, each wheel *d* being placed in a circular part *f* placed in the supports *h* and regulated by the eccentrics *j* which approximate or retire the circular part *f*, and the latter in turn the sharpening wheels *d*.
- 50 2. Improvements in machines for sharpening wooden toothpicks and like articles, as set forth in claim 1, and constituted by a set of gears *m*, *n* and *ñ*, the latter carrying a shaft with a pinion *o* meshed with the teeth that form the carriers of the toothpicks and like articles, the movement of which differs by speed from that of the central wheel *a*, actuated also by the shaft *b*.

In testimony whereof, I affix my signature.

60 MARTIN ETCHARTE, HIJO.
